UNITED STATES PATENT OFFICE.

CARL H. BISSELL, OF SYRACUSE, NEW YORK, ASSIGNOR TO CROUSE-HINDS CO., OF SYRACUSE, NEW YORK, A CORPORATION OF NEW YORK.

QUICK-BREAK SWITCH AND OPERATING MECHANISM.

Application filed January 29, 1924. Serial No. 689,370.

To all whom it may concern:

Be it known that I, CARL H. BISSELL, a citizen of the United States, and a resident of Syracuse, in the county of Onondaga and 5 State of New York, have invented a certain new and useful Quick-Break Switch and Operating Mechanism, of which the following is a specification.

This invention relates to switches and has 10 for its object a particularly simple and efficient means carried by the switch arm for giving the switch arm a quick break action, and further has for its object a particularly simple switch operating means coacting with 15 the quick break means carried by the wheel arm, which operating means can be detached from the switch and the quick break means when the switch is open and the cover of the casing for the switch, is open.

20 This invention consists in the novel features and in the combinations and constructions hereinafter set forth and claimed.

In describing this invention, reference is 25 had to the accompanying drawings in which like characters designate the corresponding parts in all the views.

Figure 1 is a side elevation of the switch casing.

Figure 2 is a sectional view on line 2—2, 30 Fig. 1.

Figures 3 and 4 are vertical sectional views of this switch and casing, the switch arm and operating mechanism being shown in open position in Fig. 3, and in closed position, Fig. 4.

This switch comprises generally a movable switch arm, a member carried by and movable with the switch arm when the switch arm is moved toward closed position and 40 relatively thereto to move the switch arm toward open position, a spring interposed between said member and the switch arm and arranged to be tensioned by the movement of said member relatively to or away 45 from the switch arm in order to give a quick break action to the switch arm and actuating means coacting with said member.

The switch arm, as here shown, comprises 50 a plurality of knives 1 hinged at 2 and a transverse bar of insulation 3 connecting the knives 1, the free ends of the knives being movable into and out of engagement with contacts 4. The knives 1 are pivoted to up- standing conductors 5 mounted on conduc-

tors 6, which are in turn, mounted upon a 55 base 7 located in a casing 8. The contacts 4 are similarly mounted on the conductors 9 mounted on the base, these conductors each being connected to wire terminals 10.

Fuse contacts 11, 12 are mounted respectively on the conductors 6 and on a similar conductor 13, the latter being connected to wire terminals 14. The switch arm here illustrated is thus a pivoted double knife switch, adapted for a two wire system, but 60 may be adapted for a three wire or other systems, or may consist of a single knife.

The member carried by the switch arm and movable with the switch arm toward 65 closed position and relatively thereto to open the switch to give a quick break action to the switch, as here illustrated, is a bar or rod 15 carried by the switch arm parallel to the bar 3 and yieldingly connected to the bar 3 by a plurality of springs 16, which are here 70 shown as tension springs, although other springs as compression springs may be used. The bar 15 is connected to the switch arm by a pin and slot connection and, as here 75 shown, the bar is guided at its ends in slots 17 formed in brackets 18 secured to the knives 1, these brackets being of insulating 80 material.

The slots 17 extend in the direction of the movement of the switch arm, that is, they 85 extend in an arc or nearly in an arc of a circle struck from the axis 2. The springs 16 normally hold the bar against the inner or lower end of the slot, which constitutes stops 90 or shoulders or limiting means of movement by the bar by the springs toward the bar 3 and form positive connections between the bar 15 and the switch arm during the closing movement of the switch arm. The opening 95 movement of the switch is limited by a stop 21 preferably carried by the upstanding conductors 5.

The means for actuating the switch arm comprises a rock shaft 22 usually journalled 100 in a side wall of the cover 23 of the case 8 and having a handle lever 24 at its outer end and a crank arm at its inner end provided with means for engaging the bar 15. The handle lever is provided with means for locking it in one of its positions, as when the switch is in open position. This locking means comprises a spring-pressed bolt 26 105 carried in a housing 27 attached to the outer

side of the cover and arranged to enter a socket 28 formed in the lever 24 when the lever is in its position assumed when the switch is "off" or "open." The bolt 26 is operated out of its holding position in which it is held by its spring 29, by a rod 30 slideable axially in the crank handle 31 on the lever 24 and the end of this rod forming the bottom of the socket 28, the rod being thrust in one direction by a spring 31^a encircling the rod and thrusting at one end against a cap or head 32 at the outer end of the rod and at its other end against the end of the crank handle 31. When the switch is in its open position, the bolt 26 enters the socket 28 and locks the handle in open position, so that it cannot fall or be shifted inadvertently to closed position. To unlock the handle, the button 32 is pressed inwardly against the action of the spring 31 far enough to press the bolt 26 out of the socket 28. The movement of the lever 24 beyond its position assumed when the switch is closed is limited by the shoulder 33 on the cover 23.

The means at the inner end of the shaft 22 for engaging the bar 15 comprising a crank arm 34 formed with a yoke 35 extending parallel to the axis of the shaft and overhanging the switch arm, the yoke 35 terminating in a radially extending arm 36 having a radially extending slot 37 for receiving the bar 15, said arm 36 having a guide 38 on the advance side of the slot, such guide being formed with an inclined surface 39 for guiding the bar 15 into the slot when the cover is being closed. The arm 36 engages the bar 15 between the springs 16.

The cover 23 is hinged at 40 to the box 8 and also has a door 41 hinged at 42 thereto, the door being opposite the fuse compartment of the box and this door 41 and the crank arm 34 are provided with means for preventing the opening of the door 41 when the switch is open and as here shown, the means consists of projections 43 and 44 on the crank arm 34 and on the door 41, such projections being arranged in each other's paths, as shown in Fig. 3, when the switch is closed and the projection 43 being arranged out of the path of the projection 44 when the switch is open, as seen in Fig. 4.

In operation, when the switch is closed and the handle 24 is operated to open the switch, the yoke 37 first moves the bar 15 into the slot 17, thus tensioning the springs 16 and when the tension of the springs 16 is sufficient to overcome the friction between the knives 1 and the contacts 4, the knives separate from the contacts with a quick break action or, in case the tension of the springs is not sufficient to initially move the knives 1 out of engagement with the contacts 4, the movement of the yoke 36 shifts the bar 15 into engagement with the outer ends

of the slots 17 and thus positively moves the knives 1 out of engagement with the contacts 4 and the springs 16 then act to give a quick break action to the knives.

What I claim is:

1. In a switch, the combination of a casing, a switch comprising a movable switch arm in the casing and means for actuating the switch arm comprising a shaft mounted in the casing, a lever mounted on the shaft 75 having a crank handle thereon, a spring-pressed locking bolt carried by the casing and the lever having a socket for receiving the bolt and means mounted on the handle and operable to press the bolt out of the 80 socket.

2. In a switch, the combination of a casing, 85 a switch, comprising a movable switch arm in the casing, and means for actuating the switch arm, comprising a shaft mounted in the casing, a lever mounted on the shaft having a crank handle thereon, a spring-pressed locking bolt carried by the casing, and the lever having a socket for receiving the bolt, and means mounted on the handle for pressing the bolt out of the socket, the last mentioned means comprising a push rod slideable axially of the crank handle and being arranged to come into alignment with the bolt when the handle is in a predetermined position, the rod being slideable axially to press the bolt out of the socket and a spring acting on the rod to resist such sliding movement thereof.

3. In a switch, the combination of a casing including a movable cover, a switch including a movable switch arm mounted in the casing a member movable with the switch arm and relatively thereto, in the same directions of movement as those of the switch arm, a stop for limiting the movement of said member relatively to the switch arm toward closed position of the switch arm, a spring tending to move said member toward said stop, actuating means 105 including a movable part carried by the cover and coacting with said member and arranged to move out of engagement with said member when the switch arm is in open position and the cover is opened.

4. In a switch, the combination of a casing, comprising a movable cover, a switch arm mounted in the casing and comprising a transverse bar, a second bar extending parallel to the first bar, a spring tending 120 to move the second bar toward the first bar, a stop limiting the movement of the second bar toward the first bar, actuating means carried by the cover and including a part coacting with the second bar and having means for preventing detachment from the second bar when the switch is closed and permits detachment therefrom upon the opening of the cover and the switch arm.

5. In a switch, the combination of a rotat-

able switch arm, a transverse bar movable with such arm, the switch arm being formed with a slot extending in the direction of movement of the switch arm, a second bar 5 arranged in the slot, springs interposed between such bars, a box in which the switch is mounted, a cover for the box, operating means carried by the cover, the operating means having a part coacting with the 10 second bar and arranged to detachably engage the same and to detach therefrom when the switch is open and upon opening of the cover.

6. In a switch, the combination of a rotatable switch arm, a transverse bar movable with such arm, the switch arm being formed with a slot extending in the direction of movement of the switch arm, a second bar 15 arranged in the slot, springs interposed between such bars, a box in which the switch is mounted, a cover for the box, operating means carried by the cover, the operating means having a part coacting with the second bar and 20 arranged to detachably engage the same and to detach therefrom when the switch is open and upon opening of the cover, said operating means comprising a 25

rock arm provided with a slot opening toward the axis of the switch arm.

7. In a switch, the combination of a rotatable switch arm, a transverse bar movable with such arm, the switch arm being formed with a slot extending in the direction of movement of the switch arm, a second bar 30 arranged in the slot, springs interposed between like ends of such bars, a box in which the switch is mounted, a cover for the box, operating means carried by the cover, the operating means having a part coacting with the second bar and 35 arranged to detachably engage the same and to detach therefrom when the switch is open and upon opening of the cover, said part comprising a rock arm provided with a slot opening toward the axis 40 of the switch arm, the slot having a guide at its open end for guiding the bar into the slot when the cover and the operating means are being closed onto the box.

In testimony whereof, I have hereunto 45 signed my name, at Syracuse, in the county of Onondaga, and in the State of New York, this 15th day of January, 1924.

CARL H. BISSELL.
